UNITED STATES PATENT OFFICE.

WILLIAM DAVID SISSON, OF NEW YORK, N. Y., ASSIGNOR TO THE AMERICAN SALVAGE COMPANY, INC., OF WEST NEW YORK, NEW JERSEY, A CORPORATION OF NEW JERSEY.

SUBMARINE VESSEL.

1,321,562.

Specification of Letters Patent. Patented Nov. 11, 1919.

Application filed June 25, 1918, Serial No. 241,767. Renewed October 13, 1919. Serial No. 330,321.

To all whom it may concern:

Be it known that I, WILLIAM D. SISSON, a citizen of the United States, residing at New York city, in the county of New York,

5 State of New York, have invented certain new and useful Improvements in Submarine Vessels; and I do hereby declare the following to be a full, clear, and exact description of the invention, such as will enable others 10 skilled in the art to which it appertains to make and use the same.

The present invention relates to improvements in submarine vessels, particularly adapted for salvage work on sunken ships.

15 In my prior Patent No. 1,184,963, dated April 6, 1915, I have shown a vessel of this type in which there is a hollow shell adapted to carry the operators of the vessel and be submerged alongside of the hull of a sunken

20 vessel to the sides of which the salvage vessel may be magnetically attached by means of magnets movably mounted upon the exterior of the shell and controlled from the interior thereof so that after the magnets

25 have been attached to the hull of a sunken vessel, the salvage vessel may be moved with respect to the sunken vessel as may be desired. The salvage vessel is also provided with a drill by means of which a hole may

30 be bored in the side of the sunken vessel and into this hole may be inserted a hook to which a chain leading to a lifting pontoon or other device may be attached. In order to permit the hook to be manipulated from

35 the interior of the shell, a magnetic member extending through the wall of the shell and to the outer end of which the hook may be attached is provided. It is intended that the salvage vessel shall be lowered from suit-

40 able supporting devices, but it is provided with a propeller and a rudder by means of which it may be navigated through the water after it has been submerged to enable it to be brought into the desired position adja-

45 cent the sunken vessel. The salvage vessel may be constructed so as to float in the water, but in order to submerge it, a comparatively heavy weight is attached to the bottom of the shell by a clutch which may be operated to release the weight to permit the shell to be easily brought to the surface in case of accident to the hoisting apparatus or any other emergencies.

The shell of the salvage vessel is also pro-

vided with suitable view ports and means 55 for illuminating the area surrounding the shell so that the progress of the salvage work may be observed.

It is a general object of the present invention to improve the mechanism of a salvag- 60

ing vessel of this type so that it may be oper- 65

ated with greater reliability and accuracy when submerged and also with increased safety for its occupants. To attain this gen- 70

eral object as well as other objects which will 75

appear more clearly hereinafter, the pres- 80

ent invention comprises a vessel of such 85

buoyancy that it will normally float in water and the shell of the vessel is provided with an opening through which entrance and 90

exit may be obtained and this opening is provided with a cover having suitable 95

clamps and an automatic arrangement for lifting the cover when the clamps are re- 100

leased so that in case of emergency the cover 105

may be quickly opened. The shell of the vessel is also provided with suitable port 110

holes and lights upon its exterior for illuminating the surroundings. It is intended that the vessel shall be suspended from suitable 115

hoisting apparatus, but since its buoyancy 120

will cause it to float in water, propellers are 125

provided for submerging the vessel. In order 130

that the vessel may be navigated when 135

submerged, other propellers and a rudder are 140

provided, and all of the propellers are driven 145

by a motor within the vessel and may be 150

suitably controlled.

The present invention also comprises an 90

improved arrangement for mounting the at- 95

taching magnets upon the vessel. In accord- 100

ance with the present invention, each mag- 105

net is attached to a carriage which is car- 110

ried by a pair of screws rotatably mounted 115

upon the exterior of the vessel and adapted 120

to be driven from within the vessel. Some 125

of the pairs of screws are placed horizontally 130

and some vertically so that either a vertical 135

or a horizontal movement may be imparted 140

to the shell with respect to a submerged sur- 145

face against which the magnets are held 150

when energized. The present invention also 155

comprises certain improvements in the mech- 160

anism for operating the drill and also in the 165

mechanism for inserting a hook in the holes 170

produced by the drill in the sides of a sub- 175

merged vessel.

The invention also includes an improved

form of hook for attaching the lifting pontoons to the side of a vessel that is to be raised.

Other features of the present invention and improvements over prior devices of this character will appear more clearly from a description of a preferred embodiment of the invention as shown in the accompanying drawings in which Figure 1 is an elevation 10 of the exterior of the vessel; Fig. 2 shows the exterior of the vessel viewed from the left of Fig. 1; Fig. 3 is a view in section along the line 3—3 of Fig. 2 showing the mechanism within the vessel; Fig. 4 is a plan view of the bottom of the interior of the vessel, the section through the shell being taken at approximately the midpoint thereof; Fig. 5 is a plan view of the mechanism mounted within the shell on a somewhat lower section plane than Fig. 4; Fig. 6 is a detailed view in section along the line 6—6 of Fig. 5; Fig. 7 is a sectional elevation of the bottom portion of the shell along the lines 7—7 of Fig. 4; Fig. 8 is a plan view 20 showing the salvage vessel held in position against the side of a submerged vessel; Fig. 9 is a plan view partly in section of the hook inserting device with a hook held thereon in position to be inserted in holes 25 in the side of a submerged vessel; Fig. 10 is an elevation partly in section along the line 10—10 of Fig. 9; Fig. 11 shows the position occupied by the hook after it has been inserted in the aperture in the side of the vessel and Fig. 12 is an end view of the hook.

Referring to the drawings in which similar reference characters denote similar parts throughout the several views, the shell of 40 the vessel, which is of sufficient strength to resist high water pressure, comprises a bottom section 20 of substantially hemispherical contour, and a top section 21 of similar contour, the two sections being connected by 45 an intermediate cylindrical section 22. Each of the sections is provided with flanges through which bolts 23 are inserted, it being understood that in practice suitable gaskets will be provided to insure water-tight joints. 50 Upon the exterior of the shell are formed lugs 24 for attaching suitable lifting chains or cables, which have not however, been shown in the drawings. Attached to the exterior of the bottom section 20 is a framework 25 constituting a standard for supporting the vessel when it is not suspended or in use. The bottom section is also provided with suitable brackets and supports for other parts of the apparatus as will hereinafter appear.

The middle section 22 is provided with suitable view port holes 26 and 27. Also mounted upon this section of the shell are brackets 28 for supporting lights for illuminating the surroundings, these lights being 65 preferably protected by cages 29.

nating the surroundings, these lights being 65 preferably protected by cages 29.

The top section 21 of the shell is provided with port holes 30 having glass windows, and an aperture serving as a passageway into and out of the shell. This aperture is provided with a cover 31 hinged at 32 and provided on its interior with clamps 33 comprising depending links adapted to fit within slots in the outer ends of lugs 34 projecting from the inner wall of the passageway. 70 Operating handles 35 are attached to the lower ends of the links and engage the under surfaces of the lugs 34 by a cam action to enable the cover to be tightly clamped in place. A suitable gasket 36 for forming a water 75 tight joint should be provided. In order that the cover may be automatically lifted when the clamps are released, it is provided with an upwardly extending portion 37 adjacent the hinge 32 and to the upper end of 80 which is attached one end of a spring 38, the other end of which is attached to a bracket 39 fastened to the outside of the shell. By virtue of this arrangement, it is only necessary for the operator to disengage the 85 clamps, after which the cover will be pulled open by the spring so that he will not have to lift the same. The upper section is also provided with a water tight gland 40 through which passes an electric cable 41 90 containing the conductors for supplying current to the apparatus within the shell.

Mounted upon a suitable frame-work 45 within the bottom section of the shell is a motor 46, the speed and direction of rotation of which may be controlled by a suitable controller 47 provided with an operating handle 48, the cable 41 being connected to the controller through suitable fuses and main switches as may be desired. The driving pulley 49 of the motor which should preferably be in the form of a sprocket wheel, is connected by means of a sprocket chain 50 to a sprocket wheel 51 on a shaft 52 supported in bearings 53 attached to the 100 frame-work in the bottom section of the shell. A sprocket 54 is loosely mounted near one end of shaft 52 and is adapted to be rotatably connected to this shaft by means of a clutch 55 having an operating handle 56 extending 105 into position to be conveniently manipulated by the operator of the vessel. Sprocket wheel 54 is connected by sprocket chain 57 to a sprocket wheel 58 on a shaft 59 supported in suitable bearings 60 projecting inwardly from the wall of the shell. Loosely mounted upon shaft 59 are pinions 61 and 62, each of which may be connected to rotate with the shaft by clutches 63 and 64 respectively, and these clutches are controlled by 115 corresponding operating levers 65 and 66. Pinions 61 and 62 mesh with pinions 67 and 68 respectively, and as shown most clearly

in Fig. 3, each of the last named pinions is attached to a shaft extending through the wall of the shell. The shaft 69 which carries the pinion 67 has at its outer end a propeller 70, while the shaft 71 which carries pinion 68 has at its outer end a propeller 72. It will be understood that the shafts 69 and 71 are carried through the walls of the shell in suitable bearings 73 provided with water-tight packing. The propellers 70 and 72 are for the purpose of navigating the vessel in a horizontal plane, but in order to steer the vessel a rudder 74 is provided. This rudder is attached to a post 75 extending through a suitable water-tight bearing in the wall of the shell and carrying at its inner end a gear 76 which meshes with a gear 77 on the end of a rod 78 provided with a steering wheel 79 in position to be conveniently reached by the operator of the vessel.

As described above, the propellers 70 and 72 are adapted to be driven from the main shaft 52 through the sprocket chain 57 under the control of clutch 55, but there is also provided another driving connection between this main shaft and the propellers so that they may be driven at a different speed than that produced by the sprocket chain 57. This alternative driving connection comprises a pinion 80 mounted on shaft 52 at the end opposite to that at which the sprocket wheel 54 is mounted. Pinion 80 meshes with a pinion 81 loosely mounted upon the end of the shaft 82 and adapted to be rotatably connected to the shaft by a clutch 83 having an operating handle 84. Attached to the other end of shaft 82 is a pinion 85 meshing with a pinion 86 upon shaft 59. There is thus formed a driving connection between main shaft 52 and the shaft 59 which may be used instead of the driving connection formed by the sprocket chain 57, it being understood that either one of these driving connections may be used as desired, and that in addition to the variations in speed of the propellers produced by these two driving connections, the speed of the motor may be governed by its controller, so that the speed of the propellers may be controlled to a degree sufficient for practical purposes. Also by virtue of the fact that the operating connections of the propellers to the shaft 59 are under the control of separate clutches 63 and 64, either or both of the propellers may be operated, so that the vessel may be steered by the propellers, if necessary.

Attached to one end of the main shaft 52 is a sprocket wheel 90 which is connected by a sprocket chain 91 to a sprocket wheel 92 on a shaft 93 mounted in suitable bearings 94. Loosely mounted on shaft 93 is a gear 95 adapted to be rotatably connected to the shaft by clutch 96 having an operating handle 97. Gear 95 meshes with a gear 98 on one end of a shaft 99. There is also

mounted upon this shaft a somewhat larger gear 100 which meshes with a gear 101 loosely mounted upon shaft 93 and adapted to be connected to this shaft by a clutch 102 provided with an operating handle 103. On account of the difference in gear ratio, between the pairs of gears 95, 98 and 100, 101, the shaft 99 may be driven from the shaft 93 at two different speeds, and by controlling the speed of the motor, the shaft 93 may be driven at different speeds, so that in practice the speed of the shaft 99 may be varied within limits as desired. Upon the shaft 99 are pinions 104 and 105 which engage gears 106 and 107 respectively, on the ends of vertical shafts 108 and 109 respectively, which pass through suitable water-tight bearings in the bottom of the shell and carry at their lower ends propellers 110 and 111. These propellers are for submerging the vessel, and in order to prevent rotation of the entire vessel about a vertical central axis, the propellers 110 and 111 are adapted to be driven in opposite directions by reversely arranging the gear teeth on pinions 104 and 105.

The free end of shaft 93 is provided with a pinion 112 engaging a pinion 113 on a shaft 114 to which is attached a sprocket wheel 115 connected by a sprocket chain 116 with a sprocket wheel 117 loosely mounted upon a shaft 118 but adapted to be connected to the latter by a clutch 119 controlled by an operating handle 120. The shaft 118 extends through a suitable water-tight bearing 121 in the wall of the shell and carries at its outer end a pinion 122 meshing with a pinion 123 upon a horizontal shaft 124 mounted in suitable bearings on the exterior of the shell. Upon shaft 124 are four pinions 125, each of which engages a pinion 126 on the end of a vertical screw 127 rotatably mounted in suitable bearings formed at the outer ends of brackets 128 projecting from the exterior of the shell. As appears most clearly in Fig. 2, these vertical screws are arranged in pairs and upon each pair is a carriage 129 provided with a support 130 to the outer end of which an electro-magnet 131 is attached. Preferably each magnet should be attached to its corresponding support by a swivel joint to permit a certain amount of movement of the magnet on the support, and each magnet should also be slidably mounted on its support and held in its outermost position by a spring 132, so that when the magnets are attached to the side of a sunken vessel, there will be a certain amount of flexibility between them and the shell of the salvaging vessel. Since any suitable form of swivel connection may be used for the magnets, the same has not been shown in detail herein.

In addition to the pairs of vertical screws mounted upon the exterior of the casing, there are pairs of horizontal screws 135, each

supported in suitable bearings at the outer ends of brackets 136 projecting from the exterior of the shell. Upon each pair of horizontal screws is a carriage and a magnet in all respects like the magnets 131 mounted upon the vertical screws, it being understood that all of the magnets are energized by current conducted over suitable cables leading from the interior of the shell where the circuits are controlled by suitable switches, it being necessary that the magnets on the horizontal screws may be energized independently of those on the vertical screws.

For the purpose of rotating the horizontal screws 135, there is associated with each of these screws, a pinion 137, each of which meshes with a pinion 138 on a vertical shaft 139 which carries near one end a pinion 140 meshing with a pinion 141 on the end of a shaft 142 extending into the shell through a suitable water-tight bearing 143 in the wall thereof. Within the shell, the shaft 142 carries a sprocket wheel 144 connected by a sprocket chain 145 with a sprocket wheel 146 loosely mounted on the shaft 118 and adapted to be operatively connected to the sprocket wheel 116 by a shifting of the clutch handle 120 in a direction opposite to that which as previously described is necessary to connect the sprocket wheel 116 in operative relation to the shaft 118 through clutch 119. There is thus provided a simple construction by which either of the shafts 118 or 142 may be operatively connected to the shaft 114 which is driven from the motor, and furthermore, the arrangement is such that both of the shafts 118 and 142 can not at the same time be connected to the shaft 114 thus preventing any possibility of simultaneous operation of the horizontal and vertical screws which would result in injury to the apparatus in case all of the magnets were energized and in engagement with a submerged surface.

In order that the operator within the shell may be advised of the extent of movement imparted to the magnets on the exterior of the shell, there is provided on the end of each of shafts 118 and 142 a traveling pointer 147, each of which is adapted to be moved back and forth along a scale 148 by a screw on the end of the corresponding shaft, the extent of movement of the index along the scale being proportional to the movement of the corresponding magnets with respect to the shell.

For the purpose of boring holes in the sides of a sunken vessel for attachment of a hook, there is provided a drill 150 on the end of a shaft 151 which passes through a sleeve 152 slidably mounted in a water-tight bearing 153 in the wall of the shell. Splined upon the inner end of the shaft 151 is a gear 154 mounted between stops 155

which also serve as bearings for the inner end of shaft 151. Gear 154 meshes with a gear 156 loosely mounted upon the main shaft 93 to which it is adapted to be connected by a clutch 157 controlled by an operating handle 158. For the purpose of feeding the drill through the side of a sunken vessel, the sleeve 152 is provided within the shell with a cross piece 159 through the ends of which are threaded screws 160 rotatably supported in suitable bearings and carrying at their outer ends pinions 161 which mesh with worms 162 on a shaft 162 to one end of which is attached a gear 163 meshing with a gear 164 on one end of a shaft 165, to the other end of which is attached a pinion 166 engaging a worm 167 loosely mounted on a shaft 93 but adapted to be rotatably connected to this shaft by a clutch 168 controlled by an operating handle 169. A pulley 170 is loosely mounted upon the other end of shaft 162 but may be connected to rotate with this shaft by a clutch 171 provided with an operating handle 172. Pulley 170 is connected by a belt to a small motor 173.

The arrangement for holding and inserting a hook within holes drilled in the side of a sunken vessel comprises a shaft 180 extending through a water-tight bearing 181 in the wall of the shell and supported at its inner end in a bracket 182. The inner end of shaft 180 is screw-threaded to receive a gear 183 which meshes with a pinion 184 loosely mounted on shaft 93 but which may be connected to rotate with this shaft by a clutch 185 controlled by an operating handle 186. In order that rotation of gear 183 may produce longitudinal movement of shaft 180, this gear is attached to the bracket 182 by means of pins 187 fitting in a groove in the hub of the gear as shown most clearly in Fig. 6. The arrangement described above will provide for longitudinal movement of the shaft 180, but since it may be necessary when inserting a hook in the holes which have been bored in the side of a sunken vessel that the shaft 180 be given a rotary movement, a hand lever 190 is splined upon the shaft 180 between the arms of a bracket 191 as shown most clearly in Fig. 6. The lever 190 is provided with a locking device 192 adapted to be inserted into teeth cut on a retaining member 193. Attached to the outer end of shaft 180 is a magnetic member for holding the hook preparatory to inserting it in holes in a submerged surface. This magnetic member comprises a base portion 195 screwed upon the end of shaft 180 and provided with washers to form a tight joint. Attached to each end of the base 195 is an electro-magnet comprising an outer shell 196, the coil 197 and a core 198, the latter being formed with a shoulder 199 near its 190

inner end adapted to engage the end of the outer shell 196, and a smaller portion which extends through the end of the shell and receives a bolt 200 for fastening the magnet 5 to the base member 195. A washer 201 is provided for making a tight joint. The magnet conductors 202 are carried through an aperture in the end of the casing 196 and then through a bore in the base member 195 and finally through a bore in the shaft 180 by which they are led into the interior of the shell to suitable controlling switches. By the provision of the washers as described, there will be no leakage of 10 water into the shell through the magnetic head and the bore in shaft 180. The outer face of each of the magnets is formed with a conical depression as at 203 adapted to receive a correspondingly shaped end of a 15 portion of the hook.

The hook used for attaching a pontoon to the side of a sunken vessel comprises a yoke 205 having the shape shown most clearly in Fig. 12, and to the central portion of which 20 a chain 206 may be connected. The enlarged ends of the yoke are each provided with an aperture as at 207 within each of which is mounted a shank 208 of the hook. Each 25 of the shanks is provided with a pointed outer end 209 and an enlarged pointed inner end 210 adapted to fit within the conical depression 203 in the face of the magnet. Along the sides of each shank are a number 30 of slots 211, the outer ends of which are undercut as at 212 to serve as sockets for retaining the ends of latching members 213 placed within the slots and adapted to be forced outwardly by springs 214. It is intended that the shanks shall be so related 35 to the yoke 200 that the latter will normally hold the latching members in place within the slots as shown most clearly in Fig. 10, and in order to prevent the yoke from dropping off of the shanks, the apertures in the 40 yoke may be provided with inclined depressions forming shoulders as at 215, which shoulders engage the outer corners of the latches when the hook is in its normal condition. The latches 213 should preferably 45 be formed with a squared portion as at 216 so that after the shank has been pushed into the hole, the latches will be forced outwardly into the position shown in Fig. 11.

While the occupants of the vessel may be 50 supplied with air through a hose leading to a pump on a tender ship at the surface, I prefer to provide the shell with means for furnishing fresh air to the occupants, so that the air supplied is independent of any surface 55 connections. For this purpose, reservoirs of compressed air or any other well known method of providing oxygen for the occupants of the shell may be used. In order to exhaust the foul air, there is provided a 60 compressor 220 driven by a motor 221 and

having its intake within the shell and its outlet communicating with a port in the wall of the shell. A relief valve 222 controlling a discharge pipe within the shell is provided in order to permit the compressor to 65 be started in case difficulty should be experienced in overcoming the external pressure. The vessel will also be provided in practice with suitable gages for indicating the depth to which it is submerged, as well as 70 gages and other instruments for indicating the pressure and condition of the air within the vessel to avoid any danger to the occupants. The vessel should also be provided with suitable signaling devices and telephones by which communication may be held 75 with the tender ship.

When the vessel is to be used for salvaging work the operators enter the same and clamp the cover in place. The vessel is then 80 lowered into the water in the vicinity of the wrecked vessel and the submerging propellers are connected to the driving motor 46 by manipulating either one of the clutch handles 97 or 103 according to the speed at 85 which it is desired the propellers shall be rotated, and as has been explained above, the motor may be governed by the controller 47 to produce other variations of speed. The propellers will draw the vessel downward 90 through the water, and since they rotate in opposite directions they will not produce any turning effect upon the shell. While it is intended that the vessel shall be connected to suitable hoisting apparatus on the tender 95 ship, it may be navigated after it has been submerged by the submerging propellers as well as by the propellers 70 and 72 and the rudder 74. As has been explained above, the driving shaft 59 for the last named propellers may be driven at either one of two 100 speeds by manipulating either the clutch handle 56 or clutch handle 84 to connect the driving connections controlled thereby to the driving shaft for the propellers. Either 105 or both of the propellers may be operatively connected to this driving shaft by manipulation of clutch handles 65 and 66, so that the propellers 70 and 72 may be used for steering the vessel, as well as for causing 110 horizontal travel of the same.

The salvaging vessel may thus be navigated until the sunken vessel is located, and it may then be further navigated along the side of the sunken vessel until a point is 115 reached at which a hook should be applied for attaching a pontoon or lifting cable. The lifting pontoons may be of any desired construction and have not been shown in the present case. The method described in my 120 prior Patent #1,134,963 may be used for carrying the pontoon to its desired location and the hooks may be suspended from buoys on the surface so that they will be approximately at the points at which they should 125 130

be applied to the sunken vessel, but it will be understood that instead of the procedure outlined in my prior patent any other method of bringing the pontoons and hooks 5 into their proper location may be used.

When the salvaging vessel is adjacent the hull of the sunken vessel at the point where a hook should be applied, it may be magnetically attached to the sunken vessel by energizing the magnets 131. During the operation of drilling a hole in the side of the vessel, all of the magnets should preferably be energized so that the thrust of the drill will not by its reaction produce any appreciable movement of the salvaging vessel. The drill is put into operation by manipulation of clutch handle 158 which controls the gears 154 and 156 for producing rotation of the drill and the clutch handle 169 which 10 controls the gears 166, 167, shaft 165, gears 164 and 163 which drive the screws 160 to advance the sleeve 152 through the wall of the shell. The drill is thus rotated and fed through the side of the sunken vessel until 15 a hole has been bored through the same. Since the advance of the drill is comparatively slow, means have been provided for producing a quick withdrawal of the drill, and this means consists of the motor 173 which through the pulley 170 and clutch 171 may be connected to drive the screws 160 in a reverse direction at rapid rate to cause the withdrawal of the drill from the hole in the side of the vessel, it being understood of course, that the gears for rotating and advancing the drill are at this time disconnected from the main driving shaft 93. Since the attaching hook comprises two shanks, it will be necessary to drill two holes 20 closely adjacent each other. It is preferred that these two holes shall be placed horizontally, although they may be placed vertically or at any other angle, if desired. If they are to be placed horizontally, the two 25 magnets 131 carried upon the pairs of vertical screws are deenergized, but the magnets carried upon the horizontal pairs of screws are energized and therefore hold against the side of the sunken vessel. By 30 suitable manipulation of the clutch handle 120, the shaft 142 may be operatively connected to the shaft 114 through the sprocket chains 116 and 145. Rotation of the shaft 142 will through pinions 141 and 140 rotate 35 the shaft 139 and thereby rotate all of the horizontal screws. Since the magnets are held against the side of the sunken vessel, this rotation of the horizontal screws will result in a horizontal movement of the 40 salvaging vessel with respect to the side of the sunken vessel, and by observing the distance traveled by means of a pointer and scale 147-148 within the shell, the amount of movement necessary to bring the drill in 45 position for the second hole may be accu-

rately determined. When the salvaging vessel has been moved the proper amount, the rotation of the horizontal screws is stopped and the magnets on the vertical screws are again energized to clamp the salvaging vessel securely to the side of the sunken vessel. The drill is then operated to bore a second hole, after which the drill is withdrawn, the magnets on the vertical screws again deenergized and the horizontal screws rotated to cause the salvaging vessel to be moved into such a position that the hook inserting device registers with the holes drilled in the side of the sunken vessel. If at any time the movement desired to be imparted to the salvaging vessel with respect to the sunken vessel is more than can be taken care of by the length of the horizontal screws, the magnets on these screws may be deenergized and the salvaging vessel held in place against the side of the sunken vessel by the magnets on the vertical screws, while the magnets on the horizontal screws are being moved toward one end of the horizontal screws, so that upon subsequent attachment to the side of the sunken vessel, the necessary horizontal movement of the salvaging vessel may take place. If the hook is held in submerged position, it may be necessary to move the salvaging vessel until the hook can be located and seized by the magnets on the end of shaft 180. After the hook has been seized by these magnets, the salvaging vessel may be moved by suitable manipulation of the horizontal and vertical screws to bring the hook into position to be applied to the side of the sunken vessel. For this purpose, the clutch handle 186 is manipulated to operatively connect gears 183 and 184 to the main driving shaft 93, and if necessary, the lever 190 may be moved to swing the two shanks of the hook into exact alignment with the holes in the side of the sunken vessel. The outward movement of shaft 180 will thrust the shanks of the hook through the holes in the side of the sunken vessel until finally they reach a position such as shown in Fig. 11, where the latches 213 will be forced outward to engage the inside of the plates of the vessel, after which the hook holding magnets 115 may be deenergized and the rod 180 retracted by reversing the driving motor to cause the shaft 93 to rotate in the opposite direction.

In Fig. 8, I have shown somewhat diagrammatically in solid lines the position 120 occupied by the salvaging vessel with respect to a submerged surface when the hole is being bored, and in broken lines, there has been shown the position occupied by the salvaging vessel and the hook retaining 125 magnets when the hook is to be inserted in the holes in the side of the sunken vessel. In this case, the movement of the salvaging vessel from the position shown in full lines to that shown in broken lines has been pro- 130

duced by rotation of the horizontal screws 135, it being understood that the magnets carried upon these horizontal screws are energized, and thus firmly held against the 5 side of the sunken vessel.

The light furnished from the lamps on the outside of the shell of the salvaging vessel will sufficiently illuminate the surroundings so that the work may be observed 10 through the observation windows in the sides of the shell. Whenever it is desired that the salvaging vessel be brought to the surface, rotation of the submerging propellers may be stopped so that the natural 15 buoyancy of the vessel will carry it to the surface of the water, and when it reaches the surface it is only necessary for the occupants to release the clamps holding the cover 31 in place when the spring 38 will 20 automatically lift the cover. While the salvaging vessel is principally intended for use in attaching lifting devices to the sides of sunken vessels, it may also be used for any kind of submarine work and since it is 25 built to withstand high water pressures, it may be used for taking observations or performing other salvaging work at depths beyond that to which divers can safely descend. It will also be understood that 30 various changes in the details of construction of the apparatus may be made without departing from the principles of the invention.

I claim:

35 1. In a submarine vessel, the combination of screws rotatably mounted upon the exterior of the vessel and magnets carried upon said screws and adapted to be moved with respect to the vessel by rotation of 40 said screws.

2. In a submarine vessel, the combination of a plurality of pairs of screws rotatably mounted upon the exterior of the vessel, a plurality of magnets each carried on 45 each pair of screws, and means for rotating the screws of each pair in unison to move the magnet mounted thereon with respect to the vessel.

3. In a submarine vessel, the combination 50 of a plurality of pairs of screws rotatably mounted upon the exterior of the vessel, means for driving the screws of each pair in unison, an electromagnet carried upon each pair of screws, and means for rotating 55 the screws of each pair in unison to move the magnet mounted thereon with respect to the vessel.

4. In a submarine vessel, the combination 60 of a plurality of pairs of screws mounted upon the exterior of the vessel, an electromagnet carried upon each pair of screws, a pinion attached to each screw, a worm gear meshing with the pinions of each pair of screws, and means for driving each of 65 said worm gears to rotate the screws of each

pair in unison and thereby move the electromagnet mounted thereon with respect to the vessel.

5. In a submarine vessel, the combination of two pairs of horizontal screws rotatably 70 mounted upon the exterior of the vessel, two pairs of vertical screws rotatably mounted upon the exterior of the vessel, a plurality of magnets, one carried upon each of the pairs of screws, means for driving both 75 pairs of horizontal screws in unison to cause horizontal movement of the magnets carried on said screws with respect to the vessel, and means for driving both pairs of vertical screws in unison to cause vertical 80 movement of the magnets carried on said vertical screws with respect to the vessel.

6. In a submarine vessel, the combination of two pairs of horizontal screws, rotatably mounted upon the exterior of the vessel, two pairs of vertical screws rotatably mounted upon the exterior of the vessel, a plurality of magnets, one carried upon each of the pairs of screws, a motor, connections for driving both pairs of horizontal 85 screws in unison to cause horizontal movement of the magnets carried thereon with respect to the vessel, connections for driving both pairs of vertical screws in unison to cause vertical movement of the magnets carried on said vertical screws with respect to the vessel, and means for selectively connecting to said motor the driving connections for said horizontal and vertical pairs 90 of screws.

7. In a submarine vessel, the combination 100 of a plurality of pairs of horizontal screws rotatably mounted upon the exterior of the vessel, a plurality of pairs of vertical screws rotatably mounted upon the exterior of the vessel, a plurality of magnets each carried upon each pair of screws, means for driving the pairs of horizontal screws in unison, means for driving the pairs of vertical screws in unison, means for independently controlling the driving means for said horizontal screws and the driving means for said vertical screws, circuit connections for simultaneously energizing the magnets carried upon the horizontal screws, circuit connections for simultaneously energizing the magnets carried upon the vertical screws, and means for independently controlling said circuit connections whereby the magnets carried by said horizontal and vertical screws 110 115 may be selectively energized.

8. In a submarine vessel, the combination of a plurality of pairs of screws rotatably mounted on the exterior of the vessel, a carriage mounted on each pair of screws, a support attached to each carriage, a magnet slidably mounted on each support and a spring associated with each support for moving the magnet outward thereon.

9. In a submarine vessel the combination 130

of screws rotatably mounted on the exterior of the vessel, electromagnets carried upon the screws and adapted when energized to be held against a submerged surface and means for rotating said screws to produce movement of the vessel with respect to the submerged surface when said electro-magnets are held against the surface.

10. In a submarine vessel, the combination of a sleeve slidably mounted in the wall of the vessel, a shaft rotatably mounted in the sleeve, a motor for rotating the shaft, a member attached to the inner end of the sleeve, screws associated with the member, means for rotating the screws in unison to move the member and sleeve, means for connecting the screw rotating means to the motor to move the sleeve and shaft through the wall of the vessel while the shaft is being rotated, a second motor and means for connecting said screw rotating means to the second motor and imparting to said screws a relatively rapid rotation to cause a quick movement of the sleeve and shaft with respect to the wall of the vessel.

11. In a submarine vessel the combination of a shaft extending through the wall of the vessel, means for imparting longitudinal

movement to the shaft without rotation thereof, a pair of electro-magnets mounted on the outer end of the shaft for holding a hook in position to be inserted in holes in a submerged surface by forward movement of the shaft, means associated with the shaft for rotating the same while permitting relative movement between the shaft and such means for changing the angular relation of the pair of magnets to the vessel, a latch associated with the shaft rotating means, and means coöperating with the latch for retaining it and the shaft rotating means in any desired position of adjustment.

12. A hook for use in connection with a submarine vessel comprising shanks provided with slots in their sides and enlarged heads, latches mounted in the slots of said shanks, springs for forcing said latches outwardly and a link provided with apertures within which the shanks are fitted with the latches normally held within the slots by the walls of the apertures.

In testimony whereof I affix my signature
June 22, 1918.

WILLIAM DAVID SISSON.
